UNITED STATES PATENT OFFICE.

WILLIAM E. McLAREN, OF CHICAGO, ILLINOIS, ASSIGNOR, BY MESNE ASSIGNMENTS, TO McLAREN-SLEIGHT CORPORATION, OF ST. JOSEPH, MICHIGAN, A CORPORATION OF MICHIGAN.

CONVERTIBLE TOY BATTLESHIP AND TANK-CAR.

1,350,417.

Specification of Letters Patent. Patented Aug. 24, 1920.

Application filed August 21, 1919. Serial No. 318,897.

To all whom it may concern:

Be it known that I, WILLIAM E. McLAREN, a citizen of the United States, residing at Chicago, in the county of Cook and State of Illinois, have invented certain new and useful Improvements in Convertible Toy Battleships and Tank-Cars, of which the following is a specification.

This invention relates to improvements in a structural and convertible toy and consists in certain novel features and peculiarities of the construction, combination arrangement and operation of the various parts thereof as will be hereinafter more fully set forth and specifically claimed.

The principal object of the invention is to provide a toy for the use and amusement of children, the parts of which shall be so constructed and may be so arranged as to afford a toy battleship of unique and attractive design, which can be readily converted into a toy tank car of the design or in simulation of the tanks or such cars used in the late war, or vice versa, which shall be simple in construction, strong, durable and highly efficient and serviceable in use or operation.

A further object of the invention is to provide a device of the above mentioned general character which will not only furnish amusement to children when used as a toy battleship or toy tank car, but which will require considerable ingenuity on the part of the user to convert the toy from one type to another, thereby educating to some extent, children, in the structural art.

Still another object is to provide simple and efficient means for locking or holding the parts of the toy securely in position without the use of nails, screws and the like, to the end, that the conversion of the device or the disassembling of its parts in one form and the reassembling of said parts in another form may be accomplished with ease and rapidity.

A still further object is to provide a detachable and self-fastening or holding axle for each of the wheels used in the convertible toy.

Various other objects and advantages of the invention will be disclosed in the following explanation and description.

In the accompanying drawings, which serve to illustrate an embodiment of the invention—

Figure 1 is a view partly in elevation and partly in longitudinal vertical section of the toy with its parts assembled to form a battleship.

Fig. 2 is a similar view showing the parts arranged in the positions they will occupy to form a toy tank car.

Fig. 3 is a plan view of the tank car, and

Fig. 4 is a cross-sectional view taken on line 4—4 of Fig. 2 looking in the direction indicated by the arrows.

Referring now to Fig. 1 of the drawings, the reference numeral 7 designates the bottom or hull of the ship, the numeral 8 the body thereof, and the numerals 9 and 10 superimposed decks, and the numeral 11 a gun turret or another deck. The three members 7, 8 and 9 are substantially of the same shape and dimensions as will be understood by reference to Figs. 2 and 3 of the drawings, and are elongated and tapered toward each of their ends. The bottom member 7 is provided near its middle in its upper surface with a pair of sockets or openings 12 which are arranged at suitable distances apart on the longitudinal axial line of said member.

Located in each of the sockets or openings 12 is the lower end of a cylindrical rod or member 13, which, when the parts are assembled to form a battleship as shown in Fig. 1 represent the smoke stacks of the ship and serve to hold the super-imposed members thereof in position against longitudinal or lateral movement. Each of the rods or smoke stacks 13 is firmly secured at its lower end to the member 7 by means of screws 14 extended through the bottom of said member and engaging the lower ends of said rods. On each of its side edges forward and aft of the transverse axial line thereof the member 7 is provided with an opening 15 which openings are for the reception of the axles 16 of the wheels 17, a pair of which wheels is located on each side of the bottom member 7 of the ship, as is clearly shown in Fig. 1 of the drawings.

Each of the members 8, 9, 10, and 11 is pro-

vided with a pair of openings 18 arranged to register with the openings or recesses 12 in the bottom member for the reception of the rods or smoke stacks 13 which extend vertically from said member.

The deck representing member 10 is considerably shorter and somewhat narrower than the member 9 on which it is mounted, and to which it is by preference permanently secured. The member 10 is provided on its upper surface with a transversely disposed rectangular recess 19 the main portion of which is located between the rods or smoke stacks 13, see Fig. 1 of the drawings, 15 which recess is provided for the purpose to be presently explained.

The uppermost member or gun turret representing member 11 is provided near each of its ends with a downwardly extended 20 transversely disposed recess 20 the purpose and use of which will soon be explained.

As shown, the member 10 is provided at each of its ends with a longitudinally extended rod 21 which are fashioned and may 25 be painted a suitable color to indicate guns or cannons. The rods 21 are by preference fixed in the member 10 and are directed forwardly and rearwardly of the device in both of the constructions thereof. Each of 30 the ends of the turret representing member 11 is provided with a detachably mounted rod 22 which may be shaped and otherwise camouflaged to simulate guns or cannons. As shown in Fig. 1 the rods or guns 22 are 35 also directed forwardly and rearwardly of the toy when the same is constructed to form a battleship.

Each of the members 7 and 8 is provided 40 forwardly of its transverse axial line near one of its edges with an opening 23 which by preference extend entirely through said members and are for the reception of the axles 16 for the wheels 17 used on the device when its parts have been converted into a 45 toy tank car as is clearly shown in Figs. 2, 3, and 4 of the drawings. Each of the members 7 and 8 is provided at its middle near its upper edge with a transverse opening 24 which are for the reception of the 50 inner ends of the detachable rods 22 which the member 11 carries at each of its ends.

Each of the axles 16 employed in the construction of the toy by preference is of the cotter-pin type, that is, each axle is divided longitudinally from its inner end to its outer end, thus forming two prongs 25 which are united at their outer ends by means of a spring loop 26 which has a tendency to expand or separate the inner portions of the prongs 25 as will be readily understood by reference to Fig. 4 of the drawing. This construction of the axles is 60 of great importance as it permits the axles to be readily inserted in the openings 15 or 23 in the members 7 and 8 in which they

will be securely held by the expansion or tendency to separate of the prongs 25 thereof.

Another important object attained by the aforesaid construction of the axle, is, that 70 when the child removes the wheels and axles from the members 7 and 8 in the operation of disassembling the parts from one form of the toy the axles will be prevented dislocation from the wheels thereby preventing 75 the loss of the axles unless the wheel carrying the same is also lost. Each of the members 7, 8 and 9 may be provided at one end thereof with an opening 27 through which 80 a cord or wire can be extended and used for pulling the device when in the battleship form, as shown in Fig. 1, for it is apparent that said openings will register with one another.

It will be understood that when the parts 85 are assembled as shown in Fig. 1 of the drawings, thereby forming the toy battleship, that the said parts will be securely held against longitudinal or lateral dislocation by means of the rods or smoke stacks 90 13 which may be painted in simulation with the smoke stacks of ships. It will also be understood that the openings 18 in each of the members mounted on the bottom member 7 is of such size as to fit snugly around 95 the rods 13 in such a manner that they will be retained in position against accidental vertical movement by the gravity of said parts and the snug fit of their openings on the said rods.

Assuming that the parts have been assembled as shown in Fig. 1 and it is desired to convert the device into a toy tank car, the following and simple operation is performed. The wheels and axles 17 and 105 16 respectively are removed from the openings in the side edges of the member 7 and the members 9, 10 and 11 are removed from the rods or smoke stacks 13 after which the members 7 and 8 are turned to rest on their 110 edges when the member 8 may be slid from the member 7 on the rods 13 which now become transverse supporting rods or members, until the outer surface of the member 8 is flush with the free ends of the rods 13, 115 see Figs. 3 and 4 of the drawings. When the members 7 and 8 which now constitute the sides of the tank car are thus positioned, the member 9, to the upper surface of which the member 10 is fixed, is placed between 120 the adjacent sides of the member 7 and 8 and will rest on the transversely extended supporting rods 13 with the recess 19 on the upper surface of the part 10 extended cross-wise of the tank car at its middle. The 125 rods or imitation guns 22 are for the instant removed from their openings in the ends of the member 11 and said member is placed cross-wise of the side members 7 and 8 so that the upper edges of said members will 130

fit into the recesses 20 on the lower surface of the member 11 near each of its ends. When this member is so applied, it will be understood that its lower portion will 5 fit in the depression 19 of the part 10 and that the openings in the ends of the member 11 will register with the openings 24 in the upper portion of the side members 7 and 8 so that the rods or imitation guns 22 can 10 be inserted through the openings in the ends of the member 11 and into the openings 24 of the side pieces.

By this arrangement it will be understood that the side pieces 7 and 8 and the members 15 9, 10 and 11 will be firmly secured together against accidental dislocation. The axles 16 of the wheels 17 can now be inserted into the openings 23 located in the side piece 7 and 8 near their lower edges when the device 20 will be completed in the form of a toy tank car.

To render the simulation of a tank car more perfect the outer surfaces of the members 7 and 8 may have displayed thereon 25 along or near their edges an imitation of a caterpillar traction belt or chain 28, which is so disposed as to indicate connection with the wheels 17 for imparting rotation thereto. As a further simulation of a tank car, the 30 sides 7 and 8 thereof may have displayed on their outer surface by means of paint or otherwise diagrams or pictures 29 and 30 of armored housings and guns protruding therefrom respectively.

Having thus fully described my invention, what I claim as new and desire to secure by Letters Patent, is—

1. In a convertible toy, the combination with an elongated bottom member, of a pair 40 of spaced apart rods fixed at one of their ends to said member and extended at right angles therefrom, a plurality of elongated members each having a pair of spaced apart and registering openings, a smaller member 45 fixedly mounted on one of the last named members and having a pair of openings in register with said other openings and provided with a transversely disposed groove between its openings, a projection in simulation of a cannon extended from each end 50 of the fixed member, another member of less size than the fixed member and having a pair of spaced apart openings to register with the other openings and provided near 55 each of its ends with a transverse recess, the last named member having at each of its ends a longitudinally extended opening therein, a rod in simulation of a cannon detachably mounted in each of said openings, 60 the said members being super-imposed one on the other in the order named with the rods on the first named member extended through said registering openings and beyond the last named member to provide the 65 effect of smoke stacks whereby a miniature

battleship, in appearance, as one form of the toy, will be provided, and whereby the removal of the member carrying the fixed part and the recessed member from the said rods can be effected, and the member adjacent to the member carrying the centrally disposed rods can be slid therefrom on said rods, and the member carrying the fixed member can be placed between said members and supported by the said rods, and the recessed member can be placed cross-wise of the thus constituted side members with its recesses engaging the upper edges of the said members and its lower portion engaging the groove in the fixed member, and so that the recessed member can be fixed to the side members by means of the detachable rods carried by the recessed member to produce, in appearance, a miniature tank car as another form of the toy.

2. A convertible toy, including in combination an elongated member having a pair of spaced apart and transversely disposed openings in each of its side edges and a pair of similarly disposed openings extended 90 therein from one of its faces near one of its edges, a wheeled axle of the cotter-pin type adapted to be interchangeably located at its inner portion in each of the openings in the edges of said member and in each of the 95 openings in the faces of said member, a pair of spaced apart rods fixed at one of their ends on said member near its middle and extended substantially at right angles therefrom, a plurality of elongated members each 100 having a pair of spaced apart openings for the reception of said rods and super-imposed one on the other and on the first named member, one of said members having a transverse groove and another of said members having a transverse recess near each of its ends, a rod in simulation of a cannon mounted on each end of the grooved member and on each end of the recessed member, the rods on the latter member being detachably 105 mounted thereon, another one of the elongated members having a pair of spaced apart openings extended therein from one of its faces, two of said wheeled axles of the cotter-pin type also adapted to be located in the 110 last named openings, all constructed, arranged and operating substantially as shown and described.

3. A convertible toy including in combination an elongated member having in each of its side edges at least one transversely disposed opening and in one of its faces at least one similarly disposed opening, an axle consisting of a pair of prongs united together at one of their ends and located in substantial parallelism with one another and having a tendency to separate at their free portions adapted for interchangeable location in the opening or openings of the 120 side edges of said member and in the open- 125

ing or openings in the face of said member, and a wheel rotatably mounted on the axle near the juncture of its prongs.

4. In a convertible toy the combination
5 with an elongated member, of a pair of spaced apart rods fixed thereto at one of their ends and extended therefrom in substantial parallelism with one another, another elongated member having a pair of
10 spaced apart openings and adapted to be movably mounted on said rods, a third elongated member having a fixed part mounted thereon between its ends, said fixed part having in its outer surface a transverse
15 groove, the last named member adapted to

be located longitudinally between the adjacent surfaces of the member carrying the said rods and the movable member and to rest on said rods, and a fourth member having near each of its ends a transverse recess 20 adapted to be located cross-wise of the other three members with its lower portion engaging the groove of the third member and its recesses engaging the upper edges of the two first named members, and means to fix 25 the fourth member in said position.

In testimony whereof, I hereunto have set my hand and seal, this 7th day of August, 1919.

WILLIAM E. McLAREN.
